US0D1043005S

(12) **United States Design Patent** (10) **Patent No.:** **US D1,043,005 S**
(45) **Date of Patent:** **** Sep. 17, 2024**

(54) **VACUUM CLEANER**

(71) Applicant: **Shenzhen Arete Dynamis Technology Co., Ltd.**, Shenzhen (CN)

(72) Inventor: **Yishun Zhong**, Danzhou (CN)

(73) Assignee: **Wonderleads Technology Shenzhen Co., Ltd.**, Shenzhen (CN)

(**) Term: **15 Years**

(21) Appl. No.: **29/871,174**

(22) Filed: **Feb. 14, 2023**

(51) LOC (14) Cl. **15-05**

(57) **CLAIM**

The ornamental design for a vacuum cleaner, as shown and described.

DESCRIPTION

FIG. 1 is a top perspective view of a vacuum cleaner, showing my new design;

FIG. 2 is a bottom perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof; and,

FIG. 8 is a bottom view thereof.

The broken lines in the drawings illustrate the portions of the vacuum cleaner, which form no part of the claimed design.

1 Claim, 8 Drawing Sheets
